UNITED STATES PATENT OFFICE.

GEORGE E. KENDALL AND WILLIAM L. COWDIN, OF DELPHI, INDIANA.

MAGAZINE-STOVE.

SPECIFICATION forming part of Letters Patent No. 749,067, dated January 5, 1904.

Application filed July 29, 1903. Serial No. 167,508. (No model.)

To all whom it may concern:

Be it known that we, GEORGE E. KENDALL and WILLIAM L. COWDIN, citizens of the United States, residing at Delphi, in the county of Carroll and State of Indiana, have invented certain new and useful Improvements in Magazine-Stoves; and we do hereby declare the following to be a full, clear, and exact description of the invention, such as will enable others skilled in the art to which it appertains to make and use the same.

This invention relates to improvements in magazine-stoves, and has for its object the production of a stove with means for supplying air in a heated condition within the casing of the stove.

Another object of the invention is to assemble means within the casing of the stove for discharging heated air directly over and in the line of combustion of the fuel contained within the fire-pot of the stove.

With these and other objects in view the invention consists in certain other novel construction, combinations, and arrangements of parts, as will be hereinafter fully described, illustrated in the accompanying drawings, and more particularly pointed out in the claims hereto appended.

In the drawings, Figure 1 is a central sectional view of the stove. Fig. 2 is an inverted detail perspective view of the air heating and supplying member assembled within the casing of the stove.

Like numerals of reference designate corresponding parts throughout both figures of the drawings.

In the drawings, reference-numeral 1 designates a stove-casing mounted upon suitable legs 2, and 3 is an escape-pipe connected with the casing at 4 and 5. Within the extension of the pipe 3, which is connected with the casing 1 at 4, is mounted a suitable damper 6. A suitable pivoted top 7 is secured to the casing 1 at 8, and mounted within said casing is a magazine 9. A bracket 10 is secured within the casing and is adapted to receive an ash-receiving receptacle 11. Said receptacle or casing 11 is provided with a flange, and said flange is adapted to receive the fire-pot 12. Interposed between the casing 11 and the fire-pot 12 is a suitable grate 13. An annular ring or supply-duct 14 is secured upon

the magazine 9. This air-supplying member 14 comprises a curved annular portion 15. Said portion is provided with a flange, formed integral therewith and extending at an angle from the bottom thereof, as designated in the drawings by reference-numeral 16. Extending at an angle and formed integral with the portion 15 is a flange or extension 17. The extension 17 is adapted to fit snugly around the magazine 9 when the member 14 is in an assembled position thereon. A lug 18 or like means is formed integral with the member 14 and is adapted to rest upon the top or outer edge of the fire-pot 12. A cylindrical member 19 is secured to the curved portion 15 of the member 14, and said cylindrical member extends from the magazine 9 to an aperture formed in the casing 1. A suitable damper 20 or sliding door 20 is secured to the outer surface of the casing 1 and is adapted to close the aperture formed for the reception of the cylindrical casing 19. A door or damper 21 is secured to the casing and is adapted to close the opening through which is passed the ash-pan 22, which is adapted to be placed within the ash-casing 11, secured within the stove-casing 1.

The fuel is supplied to the fire-pot through the magazine 9, and as the combustion takes place the smoke and flames pass around the member 14, and if it is desired to have the said combustion pass under the casings 9, 11, and 12 the damper 6 may be closed, and as the opening 5, connected with the pipe 3, is not provided with a damper the escaped vapors will pass through the same. To assist in the combustion of the fuel, the damper 20 is opened and the air containing oxygen passes into the cylindrical receptacle 19 of the annular member 14, passing therefrom into the compartment formed by the member 14 around the magazine 9 and is heated therein, and from said compartment it passes through the annular opening adjacent to the magazine 9, and from said opening the air is discharged directly above the fire-pot into the line of combustion. The heated oxygen mingles with the heated hydrogen and greatly assists the burning of the gases. By the construction shown and described we have found that the smoke which escapes from the fire-pot is greatly reduced, and if the draft, con-

trolled by the sliding door 20, is opened to the fullest extent practically no smoke at all will be caused by the consumption of the fuel in the fire-pot 12. It will be seen upon carefully examining the drawings that the fresh air containing the oxygen is directed into the annular receptacle formed by the member 14. After the same has been heated the flange 16 directs the discharge of said air against the magazine 9 and through the opening formed by the flange 16, terminating adjacent to the funnel-shaped walls of the casing 9.

The large compartment 23, formed under the assembled casings retained within the stove, provides an extra surface for the gases to come into contact with, and thereby greatly increasing the heating capacity of our improved stove. It will be obvious that the lug or extension 18, formed on the annular ring 20 or casing 14, and the member 19 of the said casing provides means for securing the said casing and the magazine 9 in a fixed position within the casing 1, as the said extension 18 engages the outer rim of the fire-pot 12 and 25 the extension or casing 19 is securely retained within the aperture formed in the casing 1.

We wish it understood that although we have described and shown in the drawings 30 our preferred form of invention we do not limit ourselves thereto, but reserve the right to make such modification as shall fairly fall within the scope of our invention.

Having thus fully described our invention, 35 what we claim as new, and desire to secure by Letters Patent, is—

1. In a device of the character described, the combination with a casing, of a magazine contained therein, a fire-pot secured beneath 40 said magazine and mounted above an ash-casing, an annular member surrounding the magazine, said member provided with an extension engaging the outer edge of the fire-pot, an annular extension formed upon the 45 upper edge of said member and encircling the wall of the magazine, an opening formed in the bottom of said member, and means secured to the member and providing an open-

ing on the same horizontal plane with the member for supplying air thereto.

2. In a magazine-stove, the combination with an outer casing, a bracket retained to the inner wall of the stove, a fire-pot mounted upon said bracket secured to said casing, a funnel-shaped magazine mounted within 55 the top of the stove and above the fire-pot, an annular member mounted upon said magazine, an extension formed upon said annular member at one side thereof and at the opposite side a cylindrical extension formed in- 60 tegral therewith and provided with means for communicating with the inner compartment of said annular member and the outer surface of the stove-casing, a flange partly inclosing the bottom of said annular casing 65 and extending at an angle from the side thereof, and means for controlling the supply of air to the annular member.

3. In a magazine-stove, the combination with an outer casing, a magazine mounted 70 within the outer casing, a fire-pot and an ash-casing assembled within the stove, a removable bracket secured to the inner face of the casing and engaging and supporting said ash-casing, a large compartment formed beneath 75 the ash-casing communicating with an escape-pipe, an annular casing surrounding the magazine and provided with a cylindrical member connecting said annular casing with the outer casing, an extension and said cylindrical member formed integral with the annular casing for retaining the same in an assembled position with the other parts, an annular opening formed in the bottom of said 80 annular casing and providing means for discharging heated air from said annular casing against the magazine-wall and into the line of combustion of the fuel contained within the fire-box.

In testimony whereof we hereunto affix our 90 signatures in presence of two witnesses.

GEORGE E. KENDALL.
WILLIAM L. COWDIN.
